KEY RING OR SIMILAR ARTICLE

Boyd E. Cousins, Kansas City, Mo.

Application September 12, 1955, Serial No. 37,879

Term of patent 7 years

(Cl. D17—14)

Fig. 1

Fig. 2

Fig. 3

Fig. 4

Fig. 1 is a front elevational view of a key ring or similar article, showing my new design;

Fig. 2 is a side elevational view thereof, the opposite side having substantially the same appearance;

Fig. 3 is a cross-sectional view thereof, to an enlarged scale, taken on line III—III of Fig. 1; and

Fig. 4 is a cross-sectional view thereof, to an enlarged scale, taken on line IV—IV of Fig. 1.

I claim:

The ornamental design for a key ring or similar article, as shown and described.
